UNITED STATES PATENT OFFICE.

CHARLES RUDOLPH NELSON, OF CHICAGO, ILLINOIS, ASSIGNOR TO C. R. & W. A. NELSON, OF CHICAGO, ILLINOIS, A FIRM COMPOSED OF SAID CHARLES RUDOLPH NELSON AND WILBUR A. NELSON.

PUNCH-PRESS.

1,319,411.

Specification of Letters Patent.

Patented Oct. 21, 1919.

Application filed January 13, 1919. Serial No. 270,874.

To all whom it may concern.

Be it known that I, CHARLES RUDOLPH NELSON, a citizen of the United States, and resident of Chicago, county of Cook, and State of Illinois, have invented certain new and useful Improvements in Punch-Presses, of which the following is a specification, and which are illustrated in the accompanying drawings, forming a part thereof.

10 The invention relates to punch presses and especially to those having a plurality of removably and adjustably held punches adapted for simultaneous operation in a variety of different arrangements with respect to their number and spacing. It is well known that in the punching of sheets for use in some forms of loose leaf binders, as for example, certain kinds of ledgers and transfer binders, a less number of 20 filing apertures or notches is required in some of the sheets than in others, although the spacing of the smaller number of apertures must be the same as the spacing of the corresponding apertures in the sheets 25 provided with the larger number. The invention accordingly contemplates a punch press having a series of removably held punches with provision permitting the removal or addition of punches intermediate the ends of the series without disturbing the spacing adjustment of those which remain.

The object of the invention is to provide an improved press for punching paper sheets and the like, the feature of improvement residing in the manner in which the cooperating parts of the punch are held in corresponding parts of the press.

In the accompanying drawings;—

40 Figure 1 is a front elevation of one form of punch press embodying the feature of improvement provided by the invention;

Figs. 2 and 3 are detail perspective views, Fig. 2 showing one of the punches with 45 some parts broken away and Fig. 3 showing an end portion of the cross head of the press;

Fig. 4 is a side elevation of the punch press, partly in section, the plane of section being indicated by the line 4—4 on 50 Fig. 1; and

Fig. 5 is a detail plan sectional view taken on the line 5—5 of Fig. 4.

The drawings show an upright punch 55 press comprising a stationary table 10 over

which is mounted a vertically movable cross head 11. The cross head 11 is guidedly held in a slideway 12 formed upon the end of an overhanging bracket arm or standard 13 and a drive shaft 14 is journaled in the standard 13 over the said slideway.

Actuation of the cross head 11 is accomplished through a link 15 which has its lower end pivotally connected to the cross head at 16 while the upper end of the link 15 is engaged with an eccentric 17 mounted on the drive shaft 14.

Inasmuch as the punching of a quantity of sheets with a variable number of filing apertures or notches at each downward thrust of the cross head 11 is contemplated, a plurality of separate punches, as 18 (Fig. 2) are preferably provided. As shown, each punch 18 is of well known construction and comprises a die block, generally designated 19, and a plunger 20. The die block 19 in turn comprises the base 21 having the die aperture 22 and the body portion 23 in which the plunger 20 is slidably mounted, the base 21 and body portion 23 being permanently connected. The plunger 20 is formed with the usual enlarged head 24.

During the operation of the press, the required number of the punches 18 are mounted therein with the upper surface of the base portion 21 of each die block 19 substantially flush with upper surface of the table 10. For this purpose the die blocks 19 of all of the said punches are rigidly clamped to the table 10 and the corresponding plungers 20 are connected to the cross head 11. Furthermore, it is important that the connection of the plungers 20 with the cross head 11 should serve for the positive actuation of the plungers by the cross head in both directions and the invention contemplates that this may be accomplished while nevertheless permitting the separate removal of any of the punches 18 without disturbing any of the others.

In the arrangement shown, all of the punches 18 are disposed in a row or series for engagement with the sheets in a straight line adjacent one edge of the same. Preferably the die block 19 of the several punches are held upon the table 10 by separate clamps. As shown, the base member 21 of each die block 19 is formed with chamfered ends 25, 26, and the table 10 is 110

grooved to provide a depressed seat 27 for the said base members, the forward edge of the groove being undercut to form an overhanging shoulder 28 for engagement with 5 the chamfered forward ends 25 of the base members. Near the rear edge of the seat 27 is a T slot 29 for receiving the head of a clamping bolt 30 by which a separate clamping plate 31 is pressed against the 10 rear chamfered end 26 of the base member 21 of each die block 19. In order that the several punches 18 may be mounted in any adjusted positions, the seat 27, shoulder 28 and T slot 29 extend continuously across the table 10 from side to side of the same.

15 The connection of the plungers 20 of the punches with the cross head 11 is accomplished by providing the said cross head with a groove 32 upon its underside. This groove preferably extends continuously throughout 20 the width of the cross head and the enlarged heads 24 of the plungers 20 enter the said groove in accordance with the location of the die blocks 19 upon the table 10.

25 Positive actuation of the plungers 20 during the upstrokes of the cross head 11 is accomplished by the use of plates 33, 34, which are carried by the cross head and extend under the enlarged heads 24 of the plungers 30 from opposite sides of the same, thereby imparting to the groove 32 the form of a T slot. One of the said plates, as 34, may be 35 permanently held in position against the corresponding part of the cross head 11, as by set screws 35.

Independent removal of any of the punches 18 is permitted by the withdrawal 40 of the plate 33 from beneath the enlarged heads 24 of the plungers 20. For this purpose the plate 33 is preferably hingedly connected to the cross head 11. As shown, the two ends of the plate 33 are upturned, as at 45 36 (Fig. 3) and each of these two end portions of the plate is pivotally attached to the corresponding end of the plunger, as by a screw stud 37. Intermediate its ends the plate 33 is formed with a plurality of upturned lugs, as 38, 39, extending along one edge of the same. The lugs 38 are normally engaged with clamping bolts 40 for holding the plate 33 against swinging movement. Each of the lugs 39, on the other hand, is apertured and is normally engaged 50 with a short stud 41 fixed in the adjacent face of the cross head 11 to prevent downward deflection of the plate 33 intermediate its ends.

In some instances it may be desirable to punch some of the sheets to be used in a 55 loose leaf ledger with a series of four filing apertures extending in a row along one edge of the sheets while other sheets are to be

punched with only two apertures corresponding in spacing with the two apertures at the ends of the row in the first mentioned sheets. With the apparatus provided by the invention the punching of both sets of sheets is readily accomplished for any of the punches 18 may be inserted or removed without disturbing the adjustment of the others. 65 For this purpose it is only necessary to withdraw the clamping bolts 40 to permit outward swinging of the plate 33 and adjust the corresponding clamping bolts 30.

75 I claim as my invention:

1. In a punch press, in combination, a co-operating table and reciprocating cross head, the said cross head being formed with a T slot the throat of which faces the table and which T slot extends continuously throughout the width of the cross head and that part of the cross head which constitutes one of the side walls of the throat of the T slot being movable to permit opening of the said throat, a plurality of separate punches each 80 comprising a co-operating die block and plunger, the plunger of each punch being formed with an enlarged head adapted to enter the T slot of the cross head through its throat when open and to be held therein when the throat is closed, and separate clamping means for removably attaching the die block of each punch to the table.

2. In a punch press, in combination, a table and reciprocating cross head, a plurality of separate punches each comprising a co-operating plunger and die block, the plunger of each punch being adjustably held by the cross head, the table having a groove 95 one side of which overhangs its bottom and there being a slot in its bottom near its opposite side, bolts anchored and slideable in said slot, the die blocks increasing in dimension toward their bases, the forward end of each being adapted to underlie the forward edge of the groove, and members abutting against the rear edge of the groove and against the rear ends of the blocks and pressed against each by nuts on said bolts.

100 3. In a punch press, in combination, a table having a groove, the front edge of which is under cut, there being a slot in the bottom of the groove near its rear edge, a bolt longitudinally slideable and anchored 105 in said slot, a die block decreasing in length from its bottom upwardly, its front end adapted to underlie the front edge of the groove, clamping means having an opening to receive said bolt and adapted to abut 110 against the rear edge of the groove and against the rear end of the die block and a nut on said bolt.

115 CHARLES RUDOLPH NELSON.
